UNITED STATES PATENT OFFICE.

THOMAS MEIKLE, OF LOUISVILLE, KENTUCKY.

COLTER-COUPLER PLATE.

SPECIFICATION forming part of Letters Patent No. 360,034, dated March 29, 1887.

Application filed January 12, 1887. Serial No. 224,138. (No model.)

To all whom it may concern:

Be it known that I, THOMAS MEIKLE, of Louisville, in Jefferson county, Kentucky, have invented new and useful Improvements 5 in Coupling-Plates for Attaching Colters to Plow-Beams, either metallic or wooden; and I do hereby declare that the following is a full and accurate account of the same.

My colter relates to that class known as 10 "caster-colters," and the object is to attain a lateral and vertical adjustment for the pivot or pintle of the caster-colter arm, whereby the point of draft for said colter may be set to the right or left horizontally, and the colter itself 15 is set up or down in a vertical plane. I am aware that these adjustments are not new; but I am not aware that they have heretofore been effected by a simple angle-plate of wrought-iron so cheaply made and easily adjusted.

20 Referring to the drawings, Figure 1 is a perspective view of my improvement. Fig. 2 is a perspective view of my coupling-plate detached. Fig. 3 is a transverse section on line x x.

25 A is the plow-beam, which may be of iron or wood, as preferred.

B is my coupling-plate, made of wrought-iron or steel, and longitudinally bent at an angle of ninety degrees, so that the part a 30 stands at right angles to the part b. The part a is provided with four rows of holes, c c, the first and third row being separated by the same distance as the second and fourth, so that the fastening-bolts d e may be used in either 35 series, as desired.

The object of the holes c in rows and series 40 is to permit the vertical and longitudinal adjustment of the coupling-plate without requiring numerous holes to be made in the beam A, and the advantage of making said plate of thin wrought-iron or steel is in its consequent capability of being put on either side of the plow-beam, and thus increase the range of lateral adjustment without increasing the lateral 45 tension of said plate. This is shown in Fig. 3. The part b is provided with a hole, f, for

a pivot-bolt, g, which attaches and centers the colter - pintle H, which is provided with an angle arm or extension, i, for the purpose of engaging the part b at a distance from the pintle H, so that the latter may be capable of a lateral swing on the pivot-bolt g. The part b is also provided with a slot, h, curved on the hole f as a center, and a bolt, j, passes through said slot and through the part i to lock and hold said part in position, but with liberty to be swung inward or outward in said slot. 50

The colter-arm K is jointed to the socket L with a horizontal joint-bolt, so that the vertical position of the colter M as to the point of 55 the plow may be changed when desired. The socket L swings freely on the pintle H, so that the colter is free to follow the plow when it changes its direction of advance.

Having described my invention, I claim— 60

1. The wrought-metal coupling-plate B, having its parts a b at right angles to each other, the part a being provided with holes c c, arranged in parallel rows and uniformly spaced, and the part b being provided with the pivot- 65 hole f and slot h.

2. In combination with the plow-beam A and the colter M, the thin angle-plate B, provided with holes c c in series and parallel rows, and with the pivot-hole f and slot h concentric 70 therewith, whereby the colter may be vertically, laterally, and longitudinally adjusted, as set forth.

3. In combination with the plow-beam A and colter M, the angle coupler-plate B, provided with the holes c c in rows and parallel series, and with the pivot-hole f and slot h, and adapted to be bolted to either side of the plow-beam, as set forth, the pintle H, having the angle part i, and the bolts g and j, to secure it to said angle coupling-plate, and the socket L, swinging freely on the pintle. 80

THOMAS MEIKLE.
